UNITED STATES PATENT OFFICE

AARON FISHMAN, OF CHICAGO, ILLINOIS

DISPLAY INSERT

Application filed June 10, 1927. Serial No. 197,886.

This invention appertains to improvements in display boxes, and it is an object of this invention to provide an improved belt display box and mounting insert for displaying a belt buckle, a watch guard, a chain, and a belt in a most advantageous manner.

The important consideration in the displaying of an article of sale is that its arrangement and setting be as attractive and pleasing as possible to invite the inspection of the prospective customer. But in addition to this, another consideration that assumes importance, particularly at rush seasons and on bargain days when stores are crowded is that of displaying the article in such a way as to make shoplifting difficult if not impossible.

A particular object of this invention is the provision of a self-locking mounting card and base support for displaying a belt buckle and a watch guard and chain, of such design that when the mounting card is placed in position on the base support, it locks itself thereto and cannot be removed without a manipulation requiring the use of both hands and also knowledge of the particular locking arrangement.

The mounting card further embodies the feature that when the watch guard and chain, and belt buckle are mounted thereon, the same are displayed to their best advantage from an artistic point of view, and yet so that they cannot be readily removed except in the reverse order in which they are mounted, which requires unclasping the watch clasp, removing the watch guard in a particular way, and unlocking the buckle, all of which is difficult to do in an underhanded manner.

Another object of this invention is the provision of an attractive display box of artistic design into which the mounting card and mounting insert displaying the belt buckle, watch guard and chain, and the belt may be placed.

The attainment of these and further objects will be apparent from the accompanying specification taken in conjunction with the drawings forming a part thereof.

Referring to the drawings, Fig. 1 shows the complete display in perspective, with the

belt and the base support holding the mounting card upon which the watch guard and chain and buckle are mounted in its position in the display box.

Fig. 2 shows the blank piece of cardboard or other suitable material of which the mounting card is made.

Fig. 3 shows the completed mounting card and the base support to which the mounting card is fastened.

Fig. 4 is an enlarged section showing the manner in which the mounting card locks itself to the base support.

Fig. 5 shows the bottom of a belt buckle fastened in position on the mounting card.

Fig. 6 is a sectional view showing the buckle in its fastened position, said view being taken along the line 6—6, of Fig. 5.

Referring first to Fig. 2, the mounting card consists of a single piece of stiff cardboard, pasteboard or any other suitable material and is cut into the shape shown in the figure. A slight knife cut is made along the lines 2, 2', 3, and 3' on the top side, and along the lines 4 and 4' on the bottom side. The incisions in each case are just deep enough to cut the surfacing to aid in bending the paper. The section 7 is now bent upwards along the line 4, and the section 7' is likewise bent upwards along the line 4'. Then sections 5 and 5' are bent and folded back to the underside of section 6. The width of section 6 is just equal to the sum of the width of sections 5 and 5'. For this reason sections 7 and 7' just about one another and are pasted together. The flaps 8 and 8' are bent along the lines 3 and 3', respectively, so that unrestrained they assume a normal position making about a 90 degree angle with the top side of section 7. The completed mounting card is shown in perspective, with a part of section 6 cut away to show the normal position of the flap 8, in Fig. 3.

The base support II, shown in Fig. 3, is made of one piece of cardboard or other suitable material, and is a bottomless box having a front edge 9 much narrower than the back edge with the two side edges tapering accordingly, as shown.

The base support has a narrow slit 12 in the center of its top 11, the length of which is

slightly longer than the length of the section 7 of the mounting card and just wide enough to allow two thicknesses of the material of which the mounting card is made to pass through, with a section (13 and 13') slightly greater than the width of flaps 8 and 8' on each end wide enough to allow three thicknesses to this material to pass through it.

To place the mounting card in position on the base support the flaps 8 and 8' are folded back and held against the face of section 7 and the projection formed by sections 7 and 7' and the flaps 8 and 8' are placed into the slot 12 in the top of the base support, the slit being shaped to accommodate the projection. After the mounting card is pushed down into the top of the base, the flaps 8 and 8' again assume their normal unrestrained position of about 90 degrees with the surface of section 7, as shown in Fig. 4. As a result, the mounting card is securely locked onto the base. It can only be removed by reaching underneath the box, again bending the flaps 8 and 8' back against the face of section 7, and while holding the flaps in this position, forcing the mounting card upward.

If desired, instead of employing a bottomless base support a bottom may be provided for the base support, making it entirely enclosed. With this arrangement, when the mounting card is once placed in position on the base support, it cannot be removed except by tearing it.

The display box, shown in Fig. 1, may be made of cardboard, or other suitable material and comprises the bottom 50 having tapered sides and a flanged base, and a cover 51 having a curvature as shown, hinged to the back edge of the flange. The taper of the container is of the same angle as that of the base support. The inside dimensions of the container are such that the base support will fit snugly in the lower portion, leaving the proper amount of space to receive the belt when wound up into an oval shaped coil and held by the looped holder 14.

The display box, of course, as well as the mounting card and base support constituting the insert may be covered with colored paper, silk, or any desired material to beautify its appearance.

The manner in which the watch guard and chain and the belt buckle are mounted on the mounting card forms one of the particular features of this invention and will now be described.

The mounting is suited for any of the popular types of buckles, but for illustrative purposes the type shown in Figs. 1, 5, and 6 has been chosen. In this type the ring 21, to which one end of the belt is ordinarily fastened, is pivoted to one end of the buckle and when turned downward from the position shown in Fig. 6, the free end of the belt may slip freely in the buckle, but when turned

up to a horizontal position, the teeth 22 grip the belt securely. To mount the belt buckle on the mounting card, the ring 21 is turned down to its unlocked position. The buckle is then slipped over the projection 23 as far as it will go, and then the ring is turned up to its locked position, thereby gripping the lip 24 in the same manner as it would the belt. As a result, the buckle is now held securely in position.

The watch guard is mounted on the projection 27 and this is done in the following manner: The watch guard is first slipped over the upper left hand corner with the upper right corner of the watch guard up against the right hand corner of the recess 28. The watch guard is then rotated in a counter clockwise direction over the lower part of projection 27 until the lower right hand corner of the watch guard is against the corner 29. The distance between the recess 28 and the lower part of the projection 27 is just long enough to make the watch guard fit snugly. It is now in position and by reason of the small projection 30 cannot be slid off the projection 27.

The watch chain fastened to the lower end of the watch guard is now brought over the top of the mounting card, is looped around the projection 31 and over the projection 32, and is clasped to the ring 21 of the belt buckle. The mounting card with its projection is made of such dimensions with respect to the parts to be displayed, that the chain after being clasped to the belt buckle will be taut thus holding the watch guard in place. The watch guard and buckle are now securely held in position with substantially the entire length of the chain attractively displayed to its full advantage.

In compliance with the requirements of the patent statutes, I have herein described a certain preferred embodiment of my invention. It is however to be understood that the same is shown for illustrative purposes only, and I do not wish to be limited to the precise construction shown.

What I consider new and desire to secure by Letters Patent is:

1. A display mounting for both a belt buckle and a watch guard of the type that may be secured to a belt and is provided with a chain to be secured to a watch, said mounting including means to which the belt buckle may be locked, and a support upon which the watch guard may be mounted, said means and said support being spaced so that upon securing the chain to the buckle when both the guard and the buckle are in position, the watch guard and buckle are irremovably locked to the mounting, the chain preventing the removal of the buckle.

2. A belt buckle display card consisting of a flat piece of paper having two projections, to one of which a belt buckle may be secured

and to the other a watch guard, a foldable locking member on the reverse side of the display card, a base support for the display card, said support having a slit therein through which the locking member may be inserted when folded, said locking member being adapted to unfold under its own resiliency after it has been inserted into place, thereby locking the display card to the base support.

3. A display card to which an article may be fastened for display purposes, said card consisting of a continuous piece of material folded upon itself with a portion of the folded part again folded to occupy a plane at right angles to the plane of the card, said last mentioned folded portion having an extension normally at right angles to itself but which may be folded into juxtaposition with it, a base support for said card, said support having a slit therein through which the last mentioned folded portion may be inserted when the extension has been folded, said extension being then adapted to unfold and lock the card to the base support.

4. A display card for mounting a belt buckle and a watch guard of the type that is provided with a chain for attachment to a watch, said card being provided with projections integral with the card for holding the buckle and the watch guard in a displayed position, and means for holding the chain tautly on the face of the card so that substantially the entire chain is displayed across the face of the card, said projections and said means being spaced so that upon securing the chain to the buckle the chain holds the buckle and the watch guard against removal from the display card.

5. The method of displaying a belt buckle and a watch guard having one end of a chain attached thereto, which comprises removably mounting the buckle to the front of a display card, mounting the watch guard upon the card, and stretching the chain across the face of the card so that substantially the entire chain is exposed on the face of the card when viewed from any angle, and securing the free end of the chain to the buckle, whereby the buckle and the guard are both locked together.

6. A display mounting for both a belt buckle and a watch guard of the type that may be secured to a belt and is provided with a chain that may be secured to a watch, said mounting comprising a substantially flat surface formed of a single sheet of material, said mounting including means to which the belt buckle may be locked, and a support upon which the watch guard may be mounted, said means and said support being spaced apart and the chain being extended across the face of the mounting and being secured to the buckle, substantially the entire chain being displayed, said mounting including means in-

tegral therewith for maintaining the chain in position across the face of the mounting.

In witness whereof, I hereunto subscribe my name this 8th day of June, A. D. 1927.

AARON FISHMAN.
